US00D788446S

(12) **United States Design Patent** (10) **Patent No.:** **US D788,446 S**
(45) **Date of Patent:** **** Jun. 6, 2017**

(54) **LOCKING DEVICE FOR SHOES**

(71) Applicant: **AIRTOX INTERNATIONAL A/S**,
Frederiksberg C (DK)

(72) Inventor: **Ariane Wiingaard-Madsen**, Vedbæk
(DK)

(73) Assignee: **AIRTOX INTERNATIONAL A/S**,
Frederiksberg C (DK)

(**) Term: **15 Years**

(21) Appl. No.: **35/500,607**

(22) Filed: **Oct. 23, 2015**

(80) **Hague Agreement Data**

Int. Filing Date: **Oct. 23, 2015**

Int. Reg. No.: **DM/089272**

Int. Reg. Date: **Oct. 23, 2015**

Int. Reg. Pub. Date: **Feb. 19, 2016**

(51) **LOC (10) Cl.** **02-07**

(52) **U.S. Cl.**

USPC **D2/978**

(58) **Field of Classification Search**
